UNITED STATES PATENT OFFICE.

CHARLES LIBERMAN, OF NEW YORK, N. Y.

LOCK.

1,368,170.

Specification of Letters Patent.

Patented Feb. 8, 1921.

Application filed March 18, 1920. Serial No. 366,741.

To all whom it may concern:

Be it known that I, CHARLES LIBERMAN, a citizen of the United States, and a resident of the city of New York, borough of Manhattan, in the county and State of New York, have invented a new and Improved Lock, of which the following is a full, clear, and exact description.

The object of the invention is to provide a new and improved lock for use on doors, trunks and other articles and devices, and arranged to prevent unauthorized persons from pushing the bolt back out of locking position by the insertion and manipulation of thin-bladed tools or other implements.

Another object is to provide a lock which is simple and durable in construction and not liable to get easily out of order.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a sectional side elevation of the improved lock mortised into a door, the section being on the line 1—1 of Fig. 2;

Fig. 2 is a cross section of the same on the line 2—2 of Fig. 1;

Fig. 3 is an enlarged sectional side elevation of the bolt in shot-out position and in engagement with the keeper;

Fig. 4 is a cross section of the same on the line 4—4 of Fig. 3;

Fig. 5 is a face view of a portion of the keeper;

Fig. 6 is a plan view of the bolt;

Fig. 7 is a cross section of the head of the bolt on the line 7—7 of Fig. 6;

Fig. 8 is a face view of the revoluble locking member for the bolt head;

Fig. 9 is a plan view of the same; and

Fig. 10 is a side elevation of a modified form of the lock applied to the outside of a door, part of the keeper being shown in section.

The lock illustrated in Figs. 1 to 9 is in the form of a mortised lock having its casing 10 mortised in a door 11 and having a keeper 12 secured to the door casing 13. In the lock casing 10 are arranged guide members 15 on which is mounted to slide a bolt 16, prefer-

ably key-controlled, in any suitable manner: for instance, as shown in Figs. 1 and 2, by the use of a rollback 17 forming part of a lock 18 mounted on the casing 10 and extending to the outer face of the door, the lock 18 being preferably of the cylinder or pin or other type.

The bolt 16 is provided with a head 20 in the form of a short twisted bar having at its inner end a shaft 21 mounted to turn in a bearing 22 formed on the forward end of the bolt 16. The shaft 21 is provided at its rear end with a head 23 abutting against the rear face of the bearing 22 to hold the head 20 against lengthwise movement but to allow the bolt to rotate in the bearing 22. It is understood that the head 20 is in close proximity to the face of the bearing 22 thus preventing rearward sliding movement of the head 20 on the bolt 16. The head 20 extends through an opening 24 formed in the face plate 25 of the lock casing 10, and the outer end of the head 20 is normally flush with the face plate 25 at the time the bolt 16 is in retracted position. The head 20 is adapted to pass into an opening 26 formed in the keeper 12 and this opening 26 corresponds in shape to the cross sectional area of the head 20, as will be readily understood by reference to Figs. 5 and 7. When the door 11 is closed and the bolt 16 is shot out then the head 20 passes into the opening 26 and as it advances in this opening the head is turned and its front portion passes into a recess 28 formed in the door casing 13, as plainly shown in Fig. 1. It will be noticed that as the head 20 fits the wall of the opening 26 in the keeper 12 it is impossible to retract the bolt 16 by the insertion of a thin-bladed tool or other implement between the keeper 13 and the face plate 25, as is so frequently practised by burglars and other unauthorized persons in jimmying a door. The forward end of the head 20 is slightly rounded off, as indicated in Figs. 1, 3 and 6, to insure a proper entering of the bolt head into the keeper opening 26 on shooting the bolt outward.

In order to provide another safeguard against turning of the bolt head 20 by unauthorized persons, use is made of a locking member 30, preferably in the form of a disk mounted to turn in a bearing 31 formed in the back of the face plate 25 of the door casing 10, and this locking member 30 is provided with a central opening 32 correspond-

ing in shape to the keeper opening 26, that is, to the cross sectional area of the bolt head 20. When the bolt 16 is advanced and the head 20 is turned on engaging the opening 26, as above explained, then the locking member 30 rotates with the head 20, and when the bolt 16 moves into an outermost position then the locking member 30 is locked against rotation thus preventing rotation of the bolt head 20. For the purpose mentioned the inner face of the locking member 30 is provided with radial slots 35, any one of which is adapted to be engaged by the free angular end 36 of a spring 37 fastened by screws or other fastening devices 38 to the inner face of the face plate 25 of the lock casing 10. The end 36 of the spring 37 is normally out of engagement with the locking member 30 and is adapted to be engaged with one of the grooves 35 by a lug 39 formed on the forward end of the bolt 16 and engaging the free end of the spring 37 at the time the bolt 16 is moved into outermost position. (See Fig. 3.) A covering plate 40 is attached to the inner face of the face plate 25 and extends over the recess 31 to hold the locking member 30 in position in the recess 31. When the bolt 16 is retracted the spring 37 returns to unlatching position relative to the locking member 30 thus allowing the latter to rotate with the head 20 of the bolt 16 during the return movement of the bolt.

The bolt 16 is held against accidental movement when in shot-out or retracted position, and for this purpose the bolt 16 is provided on top with a lug 50 adapted to be engaged by either of the notches 51 or 52 formed in a locking lever 53 mounted to swing on a pivot 54 arranged on the casing 10. A spring 55 presses on the locking lever 53 to hold the latter in engagement with the lug 50. It is understood that when the bolt 16 is in retracted position the notch 51 engages the lug 50, and when the bolt 16 is in shot-out position then the notch 52 engages the said lug 50 to hold the bolt 60 against accidental movement when in retracted and shot-out position. It is understood that the locking lever 53 does not prevent the bolt 16 from being moved into shot-out or retracted position by the roll back 17 of the key-controlled lock 18.

In case the lock is an outside lock, as shown in Fig. 10, then the casing 60 is provided with a cut-out portion 61 into which projects a keeper 62 attached to the door frame 63. The keeper 62 is provided with an opening 64 similar to the opening 26 and engaged by the head 20 of the bolt 16 when the latter is shot out thus causing the bolt head 20 to rotate as above explained, otherwise the construction is the same as above described so that further description of the same is not deemed necessary. 65

Having thus described my invention, I claim as new and desire to secure by Letters Patent:—

1. In a lock, a bolt mounted to slide and having a revoluble twisted head, a member having an opening for the passage of the bolt head, the opening corresponding to the cross sectional area of the said head to turn the latter on advancing or retracting the bolt and locking means for the said bolt head and controlled by the said bolt to lock the said head against rotation at the time the bolt is shot out. 70

2. In a lock, a bolt mounted to slide and having a revoluble head and a member having an opening engaged by the said head to turn the latter on advancing or retracting the bolt and its head, a locking member rotating with the bolt head, and means controlled by the bolt and engaging the said locking member to lock the latter against rotation at the time the bolt is shot out. 80

3. In a lock, a key-controlled bolt mounted to slide and having a revoluble and twisted head, a keeper having an opening adapted to be engaged by the said bolt head, the opening corresponding approximately in shape to the cross sectional area of the said bolt head, a locking member mounted to turn and having an opening corresponding in shape 95 to the cross sectional area of the bolt head, the latter extending through the opening of the locking member, the said locking member having face slots, a spring fixed at one end and adapted to engage one of the said 100 slots, and a lug on the bolt and adapted to engage the said spring to move the latter into locking engagement with a slot of the locking member to hold the latter against rotation at the time the bolt is shot out.

CHARLES LIBERMAN.
